(57) **CLAIM**

The ornamental design for a handle of a cooking utensil as shown and described.

DESCRIPTION

FIG. 1 is a perspective view of the handle of a cooking utensil showing our new design;

FIG. 2 is a front view thereof;

FIG. 3 is a back view thereof;

FIG. 4 is a left view thereof;

FIG. 5 is a right view thereof;

FIG. 6 is a top view thereof; and,

FIG. 7 is a bottom view thereof.

The broken lines are for the purpose of showing environmental structure only and form no part of the claimed design.

1 Claim, 7 Drawing Sheets
